UNITED STATES PATENT OFFICE.

CHRISTIAN KRÄMER, OF PANKOW, BERLIN, GERMANY, ASSIGNOR TO GENERAL ELECTRIC COMPANY, A CORPORATION OF NEW YORK.

MERCURY-ARC RECTIFIER.

Application filed May 17, 1927, Serial No. 192,130, and in Germany July 26, 1926.

My invention relates to vapor electric devices such as mercury arc rectifiers, and has for its principal object the provision of an improved arrangement whereby deterioration of the insulation between the cathode receptacle and the casing of such devices is prevented.

It is desirable for the proper working of mercury rectifiers that the cathode be perfectly insulated from the casing. Attempts have been made to attain this insulation, by building in an insulator of porcelain or the like between the cathode-holder and the housing. After a brief working period, however, of rectifiers of this kind, it has been observed that the atomizing mercury forms a conducting coating on the insulator and causes back-firing. In order to prevent the formation of a coating on the insulator, it has been proposed to build a protecting insulation member or cylinder into the cathode receptacle, which would extend partially into the cathode holder space. It was supposed that under these conditions the atomized mercury would coat only the inner wall of the protecting cylinder consisting of chamotte or other fire-proof material, while the insulator proper, between the casing and cathode space would be protected against contamination by the mercury. It is found, however, that even such an arrangement does not meet the desired requirements for the reason that the arc tends to stray from the inner mercury surface and, passing through the free crevice between the casing and the protecting ring tends to settle on the exterior surface of the mercury. In this case, owing to its great heat development, it tends to destroy the insulator and the other parts of the rectifier.

According to the invention, these disadvantages are obviated by providing projections on the protecting cylinder and on the insulator, which engage one within the other so that they form a seal or siphon-like overflow for the mercury flowing back from the casing to the cathode. With this construction, the mercury forming the closure is completely insulated, both from the casing and also from the cathode, so that the arc cannot spring over from the surface of the cathode mercury to that of the mercury exterior to the cylinder. Simultaneously, by

means of the siphon-like overflow, the mercury flowing back is freed from impurities. 55

In the accompanying drawing an embodiment of the invention is illustrated wherein *g* is a part of the housing and *k* is the cathode. The housing and cathode are separated from each other by a porcelain insulator *i*. In the cathode space a protecting screen *s* is arranged, which extends partially into the housing. The screen *s* as also the insulator *i* each possess an extension *r* opening the one upwardly, the other downwardly. The two projections *r* are in engagement, one with the other, in such manner that they form a seal or siphon-like overflow for the condensed mercury flowing 70 back in the direction of the arrow into the cathode.

The groove-like projections on the cylinder and insulator, could of course be arranged in the reversed manner to that shown 75 in the drawing. The impurities of the mercury flowing back, remain, owing to the siphon-like overflow, in the inner mercury space formed by the upper part of the insulator *i*, the screen *s* and the projection *r*. 80 The protecting cylinder *s* is maintained in its proper position by means of a spring *f* which is retained by a housing attached to the cathode receptacle. The porcelain ring *i* is advantageously made in two parts, since 85 then, the ceramic material for the ring may be better chosen.

What I claim as new and desire to secure by Letters Patent of the United States, is:—

1. A vapor electric device comprising a 90 cathode receptacle, a casing, an insulator interposed between said receptacle and said casing and provided with an inwardly projecting flange, and an insulation member extending between said receptacle and said 95 casing and provided with an outwardly extending flange, said flanges being arranged to form a seal through which mercury condensed in said casing is returned to said receptacle. 100

2. A vapor electric device comprising a cathode receptacle, a casing, an insulator interposed between said receptacle and said casing and provided with an inwardly projecting flange, an insulation member extending between said receptacle and said casing 105 and provided with an outwardly extending flange, said flanges being arranged to form

a seal through which mercury condensed in said casing is returned to said receptacle, and a resilient connection between said receptacle and said insulation member.

5 3. A vapor electric device comprising a cathode receptacle, a casing, an insulator interposed between said receptacle and said casing and provided with an inwardly projecting flange, an insulation member extend-
10 ing between said receptacle and said casing

and provided with an outwardly extending flange, said flanges being arranged to form a seal through which mercury condensed in said casing is returned to said receptacle, and a spring arranged to prevent movement 15 of said member.

In witness whereof, I have hereunto set my hand this 30th day of April, 1927.

CHRISTIAN KRÄMER.
